UNITED STATES PATENT OFFICE

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK

ADJUSTING MEANS FOR COLORED-LIGHT SIGNALS

Application filed March 14, 1923, Serial No. 625,068. Renewed October 16, 1926.

This invention relates to adjustable supporting means for light signals for railway signaling purposes.

In employing light signals for railway signaling purposes instead of the well-known semaphore signals, it is found necessary to employ a colored light beam of sufficient intensity to make it visible for a considerable distance during the day time as well as at night. In order to obtain a beam of the desired intensity in an economic manner, it is desirable to use a light concentrating device which concentrates the light into a rather narrow beam. Obviously, it is important that this beam or pencil of colored light should be directed along the track in such a direction that it can be most advantageously observed by the engineer of an approaching train. The pole or bridge structure, however, on which the light signal is mounted, will not ordinarily in practice be truly vertical. Likewise, curves or grades may require the beam to be directed in a special direction. For these and other reasons, it is desirable to provide some kind of adjustable bracket, or support, for light signals of this kind, such that the light signals are separately adjustably supported in a manner that permits the signals to have their relative position to the trackway easily and accurately changed to the desired extent.

The objects and purposes of the present invention contemplate the provision of an improved adjustable support for light signals, which permits the signals to be adjusted to any extent required in practice to the approximate correct position and which also permits the signal to be further adjusted within limited margins very accurately and to a high degree of refinement, such adjustments being made easily and in a direct and efficient manner. Other objects of the present invention contemplate the provision of a single adjustable member, which is very strong, supports the signal firmly, and facilitates adjustment of the signal in two planes substantially at right angles to each other, this member and its associated parts being constructed to permit adjustment of the signal to various positions and to firmly sup-

port the signal while such adjustments are being made, that is, without allowing intervening lost motion so that the signal at all times maintains precisely the position corresponding to the adjustment made. 55

A still further object of this invention is to provide a suitable means for indicating accurately the amount of adjustment that is being made, and also the amount of adjustment still possible before the extreme limits 60 of adjustment are reached.

Other objects, purposes, and characteristic features of the invention will be in part apparent and in part pointed out in the description hereinafter. 65

In describing the invention in detail, reference will be made to the accompanying drawing, in which:—

Figure 1 is a side elevation of a three-unit light signal supported by an adjustable support embodying the present invention; 70

Fig. 2 is an enlarged view of the adjustable supporting means shown in Fig. 1, in which parts thereof are broken away, and other parts are shown in dotted lines to illustrate its construction; 75

Fig. 3 is a partial plan view, and a partial sectional view taken on the line 3—3, Fig. 4, of the adjustable supporting means, more fully shown in Fig. 2; and 80

Fig. 4 is a sectional view taken on the line 4—4, Fig. 2, as viewed in the direction of the arrows.

Referring more particularly to Fig. 1, the adjustable support for light signals has been illustrated as applied to a three-unit multiple unit type signal comprising three signal casings S, each provided with a shield or sun-shade 1, and having a common background 2 extending the entire length of the signal. 90 These signal units are constructed so as to be interchangeable, and have their top and bottom walls provided with an opening, as shown in Fig. 4, to permit wires to be led into the several signal casings. In practice each of these signal casings is provided with a suitable light source, such as an incandescent lamp and a suitable light concentrating device, preferably comprising one or more lenses which will concentrate the light emitted from 100

the casing but will not produce a phantom indication, such as may be produced by reflection.

In the present embodiment of the invention illustrated, this multiple unit signal is supported on the signal pole 3 by a suitable adjustable support which generally comprises a base member B, fastened directly to the pole 3, and a cap member C adjustably supported on the base member and fixedly bolted to the lower unit of the signal.

The base member B comprises a main body portion 4 of general cylindrical shape having its upper portion slightly reduced and flattened, as shown at 5 in Fig. 3, and having the unflattened portion of its upper extremity reenforced on the inside and provided with an external annular groove of general rectangular cross-sectional area (see Fig. 4). In each of these grooves closely but movably fits an arcuate shoe 6 for purposes more fully described hereinafter. The internal diameter of this base member B gradually reduces near the middle portion of this cylindrical body portion to form a conical surface, as shown at 10, Fig. 2. This conical surface is adapted to rest on the top end of the signal pole 3, as shown in dotted lines in Fig. 2, so that the base member B may be turned or tilted to various positions when resting on the end of the signal pole 3.

At three equally spaced points around the lower portion of this base member B are provided bosses 7, which are drilled and tapped to accommodate set screws 8. It will thus be noted that the axial relation between the base member B and the signal pole 3 may be definitely determined by the adjustments of these set screws 8. After the adjustment between these two elements has been determined, these set screws 8 may be locked in place by lock nuts 9, thus providing a coarse adjustment which after having once been made will possibly not need to be changed again, since more refined adjustment can be made in another way.

The base member B has integral therewith an extending arm or bracket 11 provided with a vertical reenforcing rib. The outer end of this arm or bracket 11 is bossed and threaded to accommodate a bolt 13 adapted to be locked in an adjusted position by a lock nut 14.

The cap member C comprises a similar cylindrical body portion 20, which has its upper end flattened on two opposite sides only, as clearly shown in Fig. 2. This upper end of the body portion 20 of the cap C terminates in projecting perforated flanges 21 (see Fig. 4), which may be bolted to either end of a signal casing S by bolts 22.

On opposite sides of this body portion 20 and substantially in direct alignment with the flanges 21 are provided bosses 24 drilled and tapped, and containing threaded adjustable journal pins 25 adapted to be locked in

place in bosses 24 by lock nuts 26. With the cap member C in position on the base member B, the journal pins 25 extend into holes in the horizontally slidable shoes 6 and are rockable in such holes (see Figs. 3 and 4). In practice the shoes 6 and their pivot pins 25 are preferably lubricated to reduce friction and avoid rusting or corrosion. The cap member C is provided with an extending arm 28, similar to the arm 11 of the base member B, but provided with both top and bottom reenforcing ribs. Near the end of this arm is an elongated arcuate slot or opening 29 (see Fig. 3) through which the bolt 13 passes. A nut or sleeve 32, pinned to the bolt 13, limits the movement of the arm 28 downward on this bolt, whereas two nuts 33 and 34 locked together, as shown, limit the movement of the arm 28 upward.

For reasons already explained, it is an important practical consideration to be able to make certain adjustments of railway signals, particularly color light signals, so as to direct the beam of light in the proper direction. For instance, the train may approach the signal from around a curve, or on an upgrade, or on a down grade; and it will be evident that it is highly advantageous to be able to point the signal in the right direction to give the most effective indication for the particular location of that signal. Furthermore, these adjustments must be obtainable with a high degree of accuracy, because a very small movement at the signal represents a large change in the position of the beam of light at such long distances away from the signal as correspond to the range commonly desired, these distances being frequently 4,000 feet or more.

In order to make such refined adjustments to practical advantage, it is obvious that it is desirable to have some way in which the operator can easily tell when a signal is pointed in the right direction. This may be ascertained by inspection of the signal from a distance, but it is preferred to use in connection with the adjustable support of this invention a suitable sighting device by means of which the operator at the signal may determine accurately the line along which the beam of light is projected. Various types of sighting devices may be employed to advantage in connection with this invention, and no attempt has been made to show any particular type. One typical sighting device suitable for this purpose is disclosed in the application of Day, Serial No. 508,194, filed October 17, 1921.

Regarding the character of adjustment desirable in practice, it can be readily seen that the light signal may lean or tip sidewise of the vertical without particularly altering the visibility of its indication, but that it is highly important to have the signal tip forward or backward from the vertical just the right

amount in order to direct the beam of light in the proper direction, depending upon the grade and the range. Similarly, it is important to be able to turn the signal on its vertical axis to the proper position so as to direct its beam of light straight down the track or slightly sidewise to take care of a curve.

The two important adjustments above mentioned are provided for in the construction shown and described with a high degree of accuracy. Furthermore, these adjustments may be made independently of each other. The shoes 6 working in a horizontal sliding manner in the groove in the upper end of the base member B determine the vertical axis on which the signal may turn, assuming the base member B to remain stationary; and it will be noted that this axis can remain fixed independently of any change in a vertical direction in the relative position of the brackets 11 and 28. Similarly, the pivot pins 25 define a horizontal axis on which the signal may be tilted. These axes, the above mentioned vertical and horizontal axis, are preferably located at right angles to each other as shown. The purpose of brackets 11 and 28 is to permit very accurate turning of the signal on either or both of these two axes, such turning movement being obtainable separately or simultaneously as may be found most expedient to obtain a particular positioning of the signal. The refinement or accuracy of adjustment is dependent upon the length of the brackets 11 and 28, it being obvious that a movement at the outer ends of these brackets reduces a proportionally smaller movement at the signal according to the length of the brackets. The proportion of the parts illustrated is found to give as much refinement and adjustment as is necessary for ordinary conditions encountered in practice.

When installing a light signal in accordance with the present invention, after erecting the pole, changes of course may be as nearly plumb as practicable. The base member B, cap C, with the signal attached thereto, are placed on top of the pole with the brackets 11 and 28 about parallel and with the bolt 13 near the middle of the slot 29, the set screws 8 are adjusted until the signal is approximately in the correct position and is pointed substantially in the desired direction. After this coarse setting has been made, the refined adjustment is obtained by changing the relation of the brackets 11 and 28 with the aid of a suitable sighting device or other expedient.

When it is desired to turn the signal on its vertical axis so that it points straight down the track, the nuts 33 and 34 are loosened and the bracket 28 is then swung in either direction as desired. During this movement, the signal turns on the axis pro-

vided by the cooperation of the shoes 6 in their grooves. The collar 32 and the nuts 33 and 34 keep the signal from rocking forward or backward on the pivot pins 25. The graduations 36 are helpful in making this adjustment.

When it is desired to tilt the signal forward or backward, the nuts 33 and 34 are loosened slightly, sufficient to avoid cramping as the brackets 11 and 28 move toward each other; and after loosening the jam nut 14, the bolt 13 is turned in the proper direction to raise or lower the bracket 28 with respect to the bracket 11.

Among the various advantageous features of the construction embodying this invention, it is desired to emphasize the accuracy and precision with which the adjustments most important in practice can be obtained, together with the fact that the two adjustments may be made separately and independently, the adjustment on one axis not materially at least changing the adjustment on the other axis previously made. The various pivotal connections are also provided in such a manner as to permit the lead wires 37 for the various signal lamps to be carried up through the pole and into the signal casings without danger of injury to these wires while adjustments are being made. Also, the structure is so arranged as to be protected from rain and water, the cap C in particular overlapping and overhanging the base member B so as to keep out water from the lead wires and interior of the pole and signal casings.

Having shown and described one specific embodiment of the color light signal comprising several signal units and an adjustable signal support adapted for supporting various types of railway signals, and having illustrated the support applied to one particular type of signal, it is desired to be understood that various changes and modifications may be made to adapt this adjustable support to various types of signals under varying conditions encountered in practice, without departing from the spirit and scope of the invention. For instance, by slightly modifying the base member B, a signal such as illustrated may be suspended from a bridge, or the like, since opposite sides of the signal casting are identical, and in this event the cap member C and the cover on the upper signal housing will be interchanged, and the base member B may be supported directly to such bridge, or the like.

What I desire to secure by Letters Patent is:—

1. An adjustable support for signal mechanisms comprising, a stationary support having an extending bracket, a member pivotally supported on said support to swing in two different planes relative to said support, said member having a bracket substantially co-extensive with the bracket of said

support, and means for moving the outer end of one of said brackets with respect to the other in said different planes and for maintaining said brackets in their respective adjusted positions.

5. An adjustable support for railway signals comprising, a base member having means for detachably securing it to a signal pole, a pivot member on the base member, pivot means interconnecting said members to allow adjustment about two axes only substantially at right angles to each other between said two members, and a single adjustable connection between said two members 10 for locking said members in any of their 15 adjusted positions.

3. Adjustable means for supporting signals for railroads comprising, a base member, a cap member, means extending from said members connected together to form a pivoted connection between said members allowing adjustment between said members about two axes substantially at right angles to each other, said cap member being provided with 20 a skirt overhanging said pivotal connection to house said pivotal means.

4. An adjustable support for railway signals comprising, a base member having a circumferential groove, a cap member having 30 pivotal means extending therefrom and into said groove, and means extending from said two members adapted for adjusting and maintaining the relation of said two members in the two planes of movement afforded by the connection between said members.

5. An adjustable support for railway signals comprising, a base member having a peripheral groove, means slidably supported in said groove, a cap member surrounding 40 the grooved portion of said base member and having a pin extending into said means, and arms extending from said members, and means for adjustably connecting said arms together.

45. An adjustable support for railway signals comprising a base member having a peripheral groove, shoes slidably mounted in said groove, and a cap member mounted on said base member by pivot pins extending into said shoes, whereby said members may be adjusted in two different planes.

7. An adjustable support for railway signals comprising, two members relatively movable in two planes, a bracket extending 55 from each of said members, and a connecting means for the outer ends of said brackets, said connecting means having screw-threaded connection with one of said brackets and passing through an arcuate slot in the other 60 of said brackets, whereby said members may be moved to and locked in relative adjusted positions.

8. An adjustable support for railway signal casings comprising a base member secured to a fixed support and having horizon-

70 tally disposed peripheral grooves, a cap member, having a vertical axis, fitting over the base member, means carried by said cap member and engaging with said grooves on opposite sides of said base member and permitting said cap members to be turned on its vertical axis and tilted vertically relative to said base member, means for fixedly securing a signal casing to said cap member, an arm extending from said base member having a screw-threaded opening at its free end, an arm extending from said cap member and having an arcuate slot in its free end, said arms being substantially parallel, and a bolt 75 for adjustably connecting the free ends of said arms, said bolt having an adjustable screw-threaded connection with the arm on said base member, and having an adjustable sliding connection with the arcuate slot in the arm of said cap member.

9. An adjustable support for securing a railway signal casing to a fixed support comprising a base member having means for adjustably engaging said fixed support and having horizontally disposed peripheral grooves, a cap member fitting over said base member, pivotal means carried by said cap member and engaging the peripheral grooves on opposite sides of said base member, brackets extending from said base and cap members, and a bolt having an adjustable screw-threaded connection with the free end of one of said brackets and passing through an arcuate slot in the other of said brackets, said bolt carrying means for clamping said brackets in fixed relative positions, whereby said signal housing may be moved to and secured in various adjusted positions relative to said pole.

10. An adjustable support for railway signals comprising a base member detachably secured to a signal pole, a cap member, pivot means supporting said cap member on said base member to be movable with respect thereto about a vertical and a horizontal axis, and means securing said members together in any one of a number of relative adjusted positions and capable of accurately restraining said members to relative movement on either of said axes independently.

11. An adjustable support for light signals, comprising, a lower member, an upper member fixable to a light signal, an intermediate means rotatably carried by the lower member, a pivotal connection between the upper member and the intermediate means, and means including an elongated arm fixed relative to the light signal for rotatably and pivotally adjusting, in two different planes, the upper member relatively to the lower member.

12. In a light signal support, a base, means to fix the base to a support, a top member, means to fix the top member to a signal casing, a rotatable and pivotal connection only

- about axes respectively at right angles to each other between the base and top member and a single means to adjust and fix the top member relative to the base.
- 5 13. In a light signal support, a base, means to fix the base to a support, a top member, means to fix the top member to a signal casing, a rotatable connection and a pivotal connection between the base and top member and 70 means including an elongated arm fixed relatively to the signal casing and spaced from the said connection to adjust in two different planes and fix the top member relative to the base.
- 10 14. An adjustable support for railway signals, comprising a base member detachably securable to a signal pole, a cap member, pivot means supporting said cap member on said base member to be movable with respect to 75 the base member about a vertical and a horizontal axis, and means securing said members together in any one of a number of relative adjusted positions and having means permitting securing relative movement of said members on either of said axes only, said means comprising horizontal arms extending from said members, said arms having an adjustable connection.
- 15 15. A structure for supporting the casings 80 of light signals and permitting the adjustment of said signals to direct their light beams in the desired direction comprising, two members, pivot means interconnecting said members to be relatively movable in planes at right angles to each other, an extension on each member terminating at a substantial distance from the axis of the signal, and means including a threaded element associated with, and arranged for moving, said 85 extensions with respect to each other in directions corresponding to relative movement of the members in said planes.
- 20 16. In a device of the character described 90 a signal support comprising, two members, an adjustable connection between said members including a plurality of angularly positioned interconnecting axles for permitting relative movement in two different directions, two arms, extending from the members, and 95 a screw threaded connection between the outer ends of the arms permitting relative movement of the ends of said arms only in two, non-parallel, directions.
- 25 17. In a supporting structure for light 100 signals, a support, a member, means to connect said member to a signal and to pivotally connect it to said support so as to swivel about a vertical axis, said support and member having arms, and screw threaded means 105 connecting the outer ends of said arms.
- 30 18. An adjustable support for railway signals comprising, a base member detachably secured to a signal pole, a cap member, pivot means connecting the cap member to said 110 base member to be movable with respect there- 115 to about a vertical and a horizontal axis, and means extending away from the point of interconnection of said members for securing said members together in any one of a number of relative adjusted positions and including means for restraining said members to relative movement on either of said axes independently, said means comprising horizontal arms extending from said members, said arms having an adjustable connection.
- 35 19. An adjustable support for railway signals comprising a base member and a cap member, means associated with said base member for adjustably securing it to a signal pole, a double pivot means for adjustably connecting said cap member to said base member for relative movement about only two axes having a fixed angular relation, whereby 120 two separate adjustments can be made between said base member and cap member.
- 40 20. An adjustable support for railway signals, comprising two members, a plurality of angularly positioned axles interconnecting said members to allow relative movement thereof in different planes, an elongated arm 125 fixed to one member and extending away from the point of interconnection, and means on the other member for adjusting and fixing the position of the arm relative to said other member.
- 45 21. An adjustable support for railway signals, comprising two interconnected members, pivot means allowing said members to be moved relatively to each other in two directions at substantially right angles, an elongated arm fixed to one member and extending away from the point of interconnection, and means on the other member for adjusting and fixing the position of the arm relative to said other member.
- 50 22. An adjustable support for railway signals, comprising, a base member detachably securable to a signal pole, a member, double pivot connection means between said base member and said member whereby adjustment about two axes only, substantially at right angles to each other, is possible between said two members, and means for locking said members in any of their adjusted positions.
- 55 23. Adjustable means for supporting signals for railways comprising, a base member, a cap member, double pivot connection means extending from said members and connected together to form a pivoted connection between said members, said connection means including means allowing adjustment between said members about two axes only at substantially right angles to each other.
- 60 In testimony whereof I hereby affix my 125 signature.
- WINTHROP K. HOWE.
